UNITED STATES PATENT OFFICE.

JAMES TENNANT MCKEE, OF NEW BRUNSWICK, CANADA, ASSIGNOR OF ONE-HALF TO
JOHN RUSSELL THORNBERRY, OF SEAFORD, ENGLAND.

DRAFT APPARATUS FOR FURNACES.

1,318,782.

Specification of Letters Patent. Patented Oct. 14, 1919.

Application filed February 18, 1918. Serial No. 217,739.

To all whom it may concern:

Be it known that I, JAMES TENNANT MCKEE, a subject of the King of England, residing at New Brunswick, in Canada, have 5 invented certain new and useful Improvements in Draft Apparatus for Furnaces, of which the following is a specification.

This invention relates to furnaces comprising a plurality of fuel chambers each 10 having a grate intended to be fired in turn and its object is to provide that the fresh smoky products of combustion arising after the firing of one grate can be dealt with in a 15 companion chamber upon whose grate the fuel is incandescent.

The principal feature of the present invention is therefore the combination with a plurality of fuel chambers each having a grate and a wall between and separating the 20 two adjoining chambers but having in it an opening at or near the fire-door end of the wall, or blast-devices whereby the draft over any grate normally flowing directly therefrom toward the bridge, can be forced 25 reversely along that grate and caused to flow through the aforesaid opening into the companion chamber and along the grate in the latter toward the bridge.

In the accompanying drawings—

30 Figure 1 is a sectional diagrammatic plan view taken on the line 1—1 in Fig. 2 through a pair of fuel chambers according to the present invention,

Fig. 2 is a vertical section taken on the 35 irregular line 2—2 of Fig. 1 and

Fig. 3 is a sectional detailed view of a three-way valve.

In these drawings, A is a supply-pipe for air, preferably heated, derived from any 40 convenient source and leading to a valve V from which branches V¹ V² extend to what may be termed change-valves CV¹ CV², the former being allocated to the left-hand fuel chamber LH having the grate G and the 45 latter to the right-hand fuel chamber having the grate G¹. The two change-valves are controllable manually. If preferred, however, these valves may be operated automatically by any automatic control apparatus.

50 From the control-valve CV¹ a branch 1 extends through the furnace-wall and into the bridge B through which it can discharge toward the fire-door, as indicated by the arrow at the outlet O¹ in the bridge.

55 Another branch 2 extends from the change-

valve CV¹ into the chamber near the fire-door and discharges in a direction toward the bridge.

From the change-valve CV² extend branches 1^a and 2^a, respectively, similar to the branches 1 and 2 aforesaid. The branch 1^a has an outlet O^{1a} similar to the outlet O¹. Between the fuel chambers LH and RH is a division-wall W (which may be hollow, as shown) dividing the combustion space above 65 the grates into two parts but having in it an opening O at or near the fire-door end of the wall.

Although in Fig. 2 of the drawings the grates are shown as being at the under-side 70 of a cylindrical boiler L, it is to be understood that this arrangement of furnaces is equally applicable to a boiler of any suitable type.

As to the operation of the invention, let it 75 be assumed that both the grates have been charged with fuel which is burning well and that the direction of the draft from both chambers is normal and that which is indicated by the arrows ND, and next assume 80 that fresh fuel is put on to the left-hand grate G. Immediately upon the closing of the fire-door of the left-hand chamber, the change-valve CV¹ is moved into the position shown in Fig. 3 to shut off the supply of 85 air to the branch 2 and to deliver a supply along the pipe 1 which, issuing from the bridge B at O¹ reverses the draft over the left-hand grate G and propels the fresh products of combustion arising from the 90 green fuel thereon, reversely along that grate, that is to say toward the fire-door and through the opening O in the wall W into the combustion space in the companion chamber RH, so that they will flow along 95 the latter away from the fire-door over the incandescent fuel on the right-hand grate G¹ which will burn up the smoke which comes through the opening O. The change-valve CV¹ is afterward operated manually or automatically, as soon as sufficient combustion 100 on the left-hand grate is occurring, in such a manner as to restore the normal direction of draft in the left-hand chamber to that which is indicated by the arrow ND extending therefrom. Next the right-hand grate is fired and after the closing of the right-hand fire-door, the change-valve CV² is 105 operated to effect a reversal of flow in the right-hand chamber so that the fresh prod-

ucts of combustion therefrom pass through the opening O on to the left-hand chamber and flow along the latter from the left-hand fire-door toward the bridge.

5 It will be understood from the above that the freshly distilled gases in the one fire chamber are driven toward the fire door therein and into the adjacent chamber without the use of a closure device at the bridge 10 wall of the former chamber. The freshly distilled gases in the distilling chamber are thus caused to mix with the hot gases in the adjacent chamber in which latter the flow of the gases thus mixed is toward the fire 15 bridge.

Although branches 2 and 2^a are shown as being employed to enhance the normal draft, these branches can be dispensed with in cases 20 in which there is a good natural draft, leaving only the branches 1 and 1^a to bring about either the manual or automatic reversal above described.

What I claim as my invention and desire 25 to secure by Letters Patent is:—

25 1. In a furnace, the combination with a plurality of fuel chambers each having a grate and a free outlet at the bridge wall thereof, and a partition wall between and separating two adjacent chambers but having 30 in it an opening near the front or fire-door end of the wall, of forced-draft devices one opening into the rear or bridge end of each fuel chamber and directed along

the grate therein for causing the draft over the grate normally flowing directly toward the bridge wall to be reversed along that grate and forced to flow through the said opening into the adjacent fuel chamber and over the grate therein toward the bridge wall thereof, and means for controlling the 40 forced draft devices, substantially as described.

2. In a furnace, the combination with a plurality of fuel chambers each having a grate and a free outlet at the bridge wall 45 thereof, and a partition wall between and separating each two adjacent chambers but having in it an opening near the front or fire-door end of the wall, of a system of forced-draft pipes comprising two valve-controlled branch pipes opening into each fuel chamber, one of said branch pipes in each chamber opening into the front end thereof, and the other opening into the rear or bridge end thereof adjacent to the outlet 50 in the bridge wall and being directed along the grate therein for causing the draft over the grate normally flowing directly toward the bridge end to be reversed along that grate and forced to flow through the said 55 opening into an adjacent fuel chamber and over the grate therein toward the bridge end thereof, substantially as described.

In testimony whereof I affix my signature.

JAMES TENNANT MCKEE.
